UNITED STATES PATENT OFFICE.

CHARLES W. GILLESPIE, OF SAN ANGELO, TEXAS, ASSIGNOR TO THE HUNTINGTON AUTOMATIC RAILWAY CAR COUPLER COMPANY, OF TEXAS.

CAR-COUPLING.

SPECIFICATION forming part of Letters Patent No. 593,840, dated November 16, 1897.

Application filed March 29, 1897. Serial No. 629,788. (No model.)

To all whom it may concern:

Be it known that I, CHARLES W. GILLESPIE, a citizen of the United States, residing at San Angelo, in the county of Tom Green and State of Texas, have invented certain new and useful Improvements in Car-Couplers; and I do hereby declare the following to be a full, clear, and exact description of the invention, such as will enable others skilled in the art to which it appertains to make and use the same.

My invention relates to automatic car-couplers, and more particularly to that class known as "swing-pin" couplers, in which provision is made for operating the pin from the top or side of a car to uncouple the same, and also provided with a specially-formed swing-pin adapted to bear upon the link and hold it horizontally or at an incline. Heretofore it has been found difficult to provide a sufficiently strong coupler of this class, owing to the large recess required in the draw-head to accommodate the swing-pin, especially as the pin must be provided either with rearward or side extensions to obtain the necessary bearing upon the link. Again, it has generally been found necessary to make two or more openings or perforations in the draw-head for the necessary connections—one for pivoting said pin in the recess, bringing one of these openings near the mouth of the draw-head, making it liable to fracture, and the other for connecting means to operate the swing-pin and guide the link, generally made through the top of the draw-head, which exposes its interior to rain and ice. Again, in this class of couplers in order to protect the pivotal connection of the swing-pin the entire pulling strain is thrown upon one wall of the draw-head.

The object of my invention is to provide a strong and durable coupler of this class closed at the top and having no openings in its walls, with the exception of a small slot in its sides removed from the mouth of the draw-head, through which access is obtained for manipulating the pin and link.

It is also my object to reduce the size of the recess for holding the swing-pin, using one and the same means for hanging and uncoupling the pin and holding and guiding the link.

It is also my object to simplify the con-

struction and operation of the parts and give better and more direct control of the swing-pin and means for holding and directing the link.

55

It is also my object to distribute the pull upon the swing-pin between the upper and lower walls of the draw-head.

In the accompanying drawings, forming a part of this specification, Figure 1 is a side elevation of a portion of a box-car, showing my coupler attached; and Fig. 2 is an end view of the same. Fig. 3 is a side elevation of the coupler, partly in section. Fig. 4 is a horizontal section taken on the line 44 of Fig. 3. Fig. 5 is a detail view of the swing-pin.

Referring more particularly to the drawings, A denotes a car, and B the draw-head.

In Figs. 3 and 4, C denotes a recess in the draw-head, the walls of which conform to the shape and size of the swing-pin and allow for its free movement to engage the link. The upper wall of this recess slants downwardly, and its side walls are vertical. In the lower wall of the interior of the draw-head is provided a V-shaped cavity c, adapted to receive the lower end of the swing-pin. The mouth of the draw-head has the usual flare at the top and sides; but the lower portion has a deeper and more abrupt flare to admit of manipulating the link to better advantage in coupling cars having draw-heads of unequal height, as hereinafter described.

As shown in Fig. 3, the upper wall of the recess C at its forward end is reinforced by a ledge c', which extends partly under the upper end of the swing-pin and serves to prevent said end from dropping down. This reinforcement is also designed to strengthen the draw-head at this point. D D denote two curvilinear slots in opposite sides of the draw-head, arranged near its rear end.

E denotes the swing-pin, having a perforation near its lower end, through which passes hanger-bar F. The ends of said bar also pass through the slots D D and project upon opposite sides of the draw-head, about six or eight inches, where they are connected to suitable means for operating the swing-pin and link from the side of a car, as hereinafter described. The perforation in the swing-pin registers with the slots cut in the side of the draw-head,

and the slots are of sufficient length to allow the lower end of the swing-pin to rise a sufficient distance to admit the passage of the link under it and also when the link has passed under or is withdrawn to admit the lower end of the pin to bear in the V-shaped cavity. The position of the perforation in the swing-pin is such that the hanger-bar, and through it the weight of the swing-pin, will bear upon each side of the link when it is in place. Thus the weight of the swing-pin is utilized to hold the link in a horizontal position. The abrupt flare given the lower wall of the mouth of the draw-head is utilized for tilting the outer end 15 of the link up or down to meet draw-heads of different elevation. When it is desired to lower the outer end of the link, the hanger-bar is raised, thus releasing the inner end of the link from the weight of the swing-pin, 20 allowing it to rise and its outer end to tilt downwardly. It will be seen that my arrangement of the swing-pin avoids any pull on the hanger-bar and that the pull upon the swing-pin is evenly distributed between the upper 25 and lower walls of the draw-head.

In Figs. 1 and 2 I have shown means for connecting the hanger-bar to the side of a car, consisting of a rock-shaft G, extending across the end of a car, provided with crank-handles 30 and near its center having rigidly secured a crank-arm H. J denotes a chain connecting

one end of the hanger-bar to the free end of said arm. Other means may be used for operating the hanger-bar and extensions may be made for connecting operating means upon 35 the roof of the car.

Having shown and described my invention, what I claim, and desire to secure by Letters Patent, is—

1. In a car-coupler of the class described, 40 the combination of the draw-head, having curvilinear slots near its rear end upon opposite sides, and a swing-pin provided with a bar F near its lower end passing through said slots adapted to bear upon and hold the link 45 in position for coupling, and means for operating said bar.

2. In a car-coupler of the class described, the combination of the draw-head having a ledge c' in the upper portion of its mouth, 50 curvilinear slots upon opposite sides near the rear end of the draw-bar, and a swing-pin having its upper end resting upon said ledge, its lower end provided with a hanger-bar passing through said slot and means for operating 55 said bar.

In testimony whereof I have affixed my signature in presence of two witnesses.

CHARLES W. GILLESPIE.
